UNITED STATES PATENT OFFICE.

GUSTAVE LYON, OF PARIS, FRANCE, ASSIGNOR TO SOCIÉTÉ ANONYME PLEYEL, OF PARIS, FRANCE, A CORPORATION OF FRANCE.

MECHANICAL CONSTRUCTION OF PIANOS.

Application filed January 27, 1927, Serial No. 164,067, and in France March 26, 1926.

My invention relates to improvements in the mechanical construction of pianos comprising two keyboards disposed one above the other, the keys of the upper keyboard being situated in the rear of the keys of the lower keyboard.

It is an observed fact that in the mechanical construction of pianos with double keyboard, the latter is so arranged that the keys of the lower keyboard will act directly upon the striker mechanism of the note situated in the same plane, and that the keys of the upper keyboard will act by suitable transmission means upon the striker mechanism of the note which is situated for instance an octave higher than the note controlled by the lower keyboard. Further, it is feasible, by suitable coupling means, to connect the mechanism of the upper keyboard with that of the lower keyboard, while acting upon this latter, at the same time permitting the independent operation of the keys of the upper keyboard, in such manner that by pressing a key corresponding to a note produced by the lower keyboard, the operator can produce this note as well as the note situated an octave higher, while being able at the same time to separately press any of the keys of the upper keyboard.

My said improvements essentially consist in the construction of the different devices in a simple manner, thereby reducing the risks of defective operation and rendering the mechanical parts easy of access for mounting and dismounting.

One of the principal characteristics of the invention consists in the use of a coupling device which permits, by pressing a given key of the lower keyboard, to produce at the same time the corresponding note and the note situated an octave higher, while the operator is further enabled to press the keys of the upper keyboard in an independent manner.

The invention is clearly disclosed in the following description with reference to the appended drawings.

Fig. 1 is a general cross section of the apparatus in accordance with the invention.

Fig. 2 is the corresponding plan view.

Fig. 3 is a diagrammatic perspective view of the transmission device of the upper keyboard.

Figs. 4 and 5 are detail views showing two positions of the device which serves to couple the lower key with the gear pertaining to the corresponding key of the upper keyboard.

The two keyboards are in all cases disposed one above the other and comprise the requisite number of keys. The lower keyboard consists of the white keys a^1 a^2 etc. and the black keys A^1 A^2 etc., and the upper keyboard consists of the white keys b^1 b^2 etc., and the black keys B^1 B^2 etc.

The keys of the upper and lower keyboards are respectively disposed one in the rear of the other and in the same plane as the mechanism which serves to control each striker corresponding to a respective key.

The keys a^1 or A^1 of the lower keyboard, when turning upon their pivots, will raise by their respective ends 28 a lever 16 coacting with an adjustable button 29 which is mounted on the rod 1 whose upper end is secured to the lever 2 controlling the striker mechanism. In this manner the keys of the lower key board will directly actuate each corresponding striker mechanism.

In the lever 16 (Figs. 1, 4 and 5) is formed a mortise 32 whose function will be further disclosed. The ends of the keys b^1 or B^1 of the upper keyboard are provided with a respective adjustable button 7 coacting with the lever 16; a mortise 3 is formed in the said lever (Figs. 2 and 3) for the free passage of the rod 1 which is controlled by the keys of the lower keyboard.

The lever 16 (Figs. 1 and 3) is connected by a link 20 with a member 6¹ which forms one branch of a piece 8 having an elongated U shape which is pivoted on the horizontal axle 5 and is terminated at the other end by a member 6 similar to the member 6¹. The space between the branches 6 and 6¹ of the piece 8 is determined in such manner as to correspond to the space which is necessary to contain all the mechanisms of an octave of notes.

The rotation of the piece 8 on its axle 5, due to the ascent of the branch 6¹ under the action of the link 20 coacting with the lever 16¹ which is raised by the button 7 mounted on the end of a key b^1 or B^1 , will thus raise the second branch 6 by a like amount.

The upper face 3 (Fig. 8) of the branch

6 is in contact with the button 12 which is screwed upon the rod 1—which as above stated connects the lever 16 of the lower keyboard with the lever 2 controlling the 5 striker mechanism—and in this manner the device actuates the striker mechanism of the note which is an octave higher than the note corresponding to the key of the lower keyboard situated directly below the key 10 which is pressed upon the upper keyboard.

It will be observed from what precedes that upon pressing a key b^1 or B^1 of the upper keyboard, this will actuate, through the mechanism 6¹—8—6, the striker for the 15 note situated an octave higher, i. e., the striker of the twelfth key counting to the right, which striker can further be directly controlled by a key a^2 or A^2 of the lower keyboard.

20 A coupling device is employed to connect together the levers 16 and 16¹ which are respectively controlled by the keys of the upper and lower keyboards, so as to produce simultaneously the note corresponding to the 25 directly actuated key and the note corresponding to the upper octave.

To effect this coupling, i. e., to connect together the levers 16 and 16¹, there is pivotally mounted at 15¹ on the lever 16¹, a 30 vertical lever 15 whose lower end normally projects through the mortise 32 provided in the lever 16. A spring 34 has its upper end connected to the lever 16¹ while the lower portion bears against the lever 15 so as to 35 move the shoulder portion 15² of the lever in engagement with the end 32¹ of mortise 32, as shown in Fig. 5.

This coupling movement is under the control of a pedal (not shown) which as represented in Figs. 4 and 5 will move to the right 40 a bar 33 coacting with all of the vertical levers 15, so that the spring 34 (in each case) can act upon the pieces 15, in order to bring the lower end 15² upon the edge 31¹ of the 45 mortise 32 formed in the lever 16.

When the pedal ceases to act upon the bar 33, the latter will drive back all of the vertical levers 15 against the action of the 50 springs 34, so that the lower ends 15² will coincide with the mortises 32 in the levers 16. In this position, the ascent of the lever 16 will have no effect upon the lever 16¹, since the vertical lever 15 is freely engaged in the mortise 32 in each case.

55 The lower ends 31 of the rods 1 are loosely slidable (Fig. 5) in the apertures 35 formed in the levers 16, so that in the coupled position, the lever 16 of the upper octave will not be actuated during the ascent of the rod 1 due to the button 12. During the ascent 60 of the rod 1, it will simply move within the aperture 35 of the lever 16. If the apertures 35 were not provided, and the rod 1 were simply secured in the lever 16, the lever 16

situated in the upper octave would impart 65 its motion to the octave above the latter, and so on, and thus the motion would be transmitted from upper octave to upper octave towards the right, and clear to the end of 70 the keyboard.

From the preceding considerations it will be observed (Figs. 4 and 5) that when the vertical lever 15 is driven back by the bar 33 against the action of the spring 34, its lower end 15² will be disengaged from the edge 32¹ of the mortise 32 in the lever 16, so that the ascent of said lever will not affect the lever 16¹, and thus when a key a^1 or A^1 of the lower keyboard is pressed, this will only control—through the rod 1—the striker 80 mechanism of the note situated in the same vertical plane. It will be noted that the rods 1 are loosely movable in the mortises 3 (Figs. 2 and 3) in the lever 16¹ and in the forks 6 of the U-shaped pieces 8.

The descent of a key b^1 or B^1 of the upper keyboard will act directly upon the corresponding lever 16¹ which—by means of the rod 20—will raise the branch 6¹ of the piece 8 (Fig. 3) which will thus turn upon its pivot 5, and this movement will raise the second branch 6 situated in the plane of the mechanism of the note in the upper octave (Fig. 3). As above stated, the rod 1 is engaged in a slot in the said branch, and a button 12 mounted on said rod is in contact with the upper face of the branch 6. The ascent of the branch 6 will thus act upon the button 12 and hence upon the rod 1, and the latter will thus control the striker mechanism of the note. When the rod 1 is raised by the branch 6, its lower part will move freely in the mortise 3 of the lever 16¹ and in the aperture 35 of the lever 16.

For the coupling of the levers 16 and 16¹, 105 the operator acts by means of a pedal upon the bar 33 which will thus be moved to the right. Under the action of its spring 34 the vertical lever 15 will turn on its pivot 15¹ upon the lever 16¹, and its lower end 15² will be displaced in the mortise 32 and will be brought upon the edge 32¹ of the lever 16.

At this moment, if the operator presses a key a^1 or A^1 of the lower keyboard, this will act upon the lever 16 which in its ascent 115 will actuate—by the button 29—the rod 1 connected with the lever of the striker mechanism for the corresponding note, and at the same time, due to the coupling afforded by the vertical lever 15, the lever 16¹ will be raised and hence (through the rod 20, the branch 6¹ of the U-shaped piece 8, and the second branch 6) it will act upon the button 12 of the rod 1 which actuates the control lever 2 of the striker mechanism of the note an octave higher than the note which is directly controlled by the lever 16.

Irrespectively of the coupling thus ef-

fected, it will always be feasible to directly actuate the keys b^1 B^1 etc. of the upper keyboard.

Claims:

- 5 1. In a coupling device, for pianos provided with a lower keyboard the keys of which act directly upon the striker mechanism of the note situated in the same plane and an upper keyboard the keys of which 10 act upon the striker mechanism of the note situated an octave higher than the note controlled by the keys of the lower keyboard, providing for the simultaneous operation of the striker mechanism actuated by any of 15 the keys of the lower keyboard and of the striker mechanism of the note situated an octave higher than the note controlled by the key of the lower keyboard without affecting the corresponding key of the upper keyboard, 20 a coupling piece between the lever actuated by the keys of the lower keyboard and the lever actuated by the keys of the upper keyboard, a pivot for the coupling piece on the lever actuated by the keys of the upper keyboard.

the upper keyboard, a mortise formed in 25 the lever actuated by the keys of the lower keyboard, a bar normally holding the coupling piece in coincidence with the mortise, and an external pedal controlling the bar.

2. In a coupling device as claimed in claim 1, a coupling piece between the lever actuated by the keys of the lower keyboard and the lever actuated by the keys of the upper keyboard, a pivot for the coupling piece on the lever actuated by the keys of the upper keyboard, a mortise formed in the lever actuated by the keys of the lower keyboard, a bar normally holding the coupling piece in coincidence with the mortise, an external pedal controlling the bar and a spring mounted on 40 the lever actuated by the keys of the upper keyboard and coacting with the coupling piece, when the bar is disengaged, so as to engage the lower end of the coupling piece upon one edge of the mortise. 45

In testimony whereof I affix my signature.

GUSTAVE LYON.
